BY

L. L. Westfall Jr. ATTORNEY

UNITED STATES PATENT OFFICE.

LUCENA STAFFORD, OF SPOKANE, WASHINGTON.

HAIR-DYER.

No. 877,960.

Specification of Letters Patent.

Patented Feb. 4, 1908.

Application filed June 25, 1907. Serial No. 380,705.

To all whom it may concern:

Be it known that LUCENA STAFFORD, a citizen of the United States, residing at Spokane, in the county of Spokane and State of Washington, has invented certain new and useful Improvements in Hair-Dyers, of which the following is a specification.

This invention relates to hair dyers, and has for its object, to provide a device where-
10 by a few hairs, or a single hair, for that matter, may be dyed without necessarily expos-
ing to the dye, the entire body of the hair of
the head. For instance, a few hairs may
have turned white or gray and it is desired to
15 dye these hairs the same color of the remain-
ing hairs of the head, then by the use of this
device the gray or white hairs may be dyed
without the necessity of applying the dye to
the entire head of hair, thereby avoiding cer-
tain injurious effects to the hair.

In the accompanying drawings I have
shown my device.

Figure 1, is an elevation of the device,
Fig. 2 is a side elevation of the same, Fig. 3 is
25 an enlarged elevation of the end of one of the
prongs of the device, Fig. 4 is a cross-section
of the same and Fig. 5 is an elevation of one
of the pads or cushions secured to the end of
the prongs.

30 The main body of my device might be said
to consist of a flat piece of steel bent into the
shape of a hair-pin, or into the shape of the
letter **U**, approximately, but elongated, as
indicated in the drawings at 10, with a pad or
35 cushion 11 secured to each end thereof, on
the inside, so that the two pads or cushions
may be brought into contact with each other
by the pressing together of the two prongs of

the device. In order that the pads or cush-
ions may be removed and replaced by others, 40
I have provided a piece of steel 12 and se-
cured the same to the inner surface of the
ends of the prongs of the device, the edges 13
of the steel 12 being slightly curled upward
and inward, to serve as a retaining means for 45
the pads or cushions and also permit of their
removal by hand.

When it is desired to use the device in
dyeing, it is only necessary to saturate the
pads or cushions 11 with the proper liquid 50
dyeing material, take the device in the
hand, grip the hair to be dyed at the surface
of the scalp by the open end of the device and
pass the pad or cushion portion along the
hair to the end thereof, repeating this opera- 55
tion until the desired result is obtained.

Having thus described my invention, what
I claim as new and useful and desire to se-
cure by Letters-Patent is,

In a device for dyeing hair, an approxi- 60
mately **U** shaped member, elongated, pro-
vided at the open end thereof with a pad or
cushion on the inner surface of each prong,
such pads or cushions being retained in their
positions by a member engaging their side 65
edges and a portion of their exposed surfaces
said member being attached to the prongs of
the said **U** shaped member, substantially as
set forth.

In testimony whereof I have affixed my 70
signature, in presence of two witnesses.

LUCENA STAFFORD.
